[57] CLAIM

The ornamental design for a twin-nibbed ball-point pen, as shown and described.

DESCRIPTION

FIG. 1 is a top, left front perspective view of a twin-nibbed ball-point pen showing my new design in an exploded condition;

FIG. 2 is a front elevational view thereof;

FIG. 3 is a top plan view thereof;

FIG. 4 is a bottom plan view thereof;

FIG. 5 is a left side elevational view thereof; and,

FIG. 6 is a right side elevational view thereof.

FIG. 1

FIG. 2

FIG. 3

FIG. 4

FIG. 5

FIG. 6
